FLAME, EMBER AND RAIN RESISTANT VENT INSERTS FOR ROOF VENTS

FIELD OF THE INVENTIONS

The inventions described below relate to the field of flame, ember and weather resistant retrofit assemblies for installed roof vents.

BACKGROUND OF THE INVENTIONS

Energy efficiency is a serious consideration in every building. Residential buildings require attic ventilation systems to minimize heat and moisture buildup within attics. However, as attic ventilation technology improves building with existing "old-technology" ventilation systems hesitate to break the moisture barrier of their roof to replace the vents when improvements are available, it is often less expensive to replace the entire roof as well as the vents than to try and remove and replace old vents and then reseal the roof. In areas with extreme weather, rain, fire and embers, these undesirable elements are often driven into and through attic ventilation systems causing damage to the building, sometimes completely destroying it. This is a positive motivation to replace outdated ventilation technology, unfortunately replacing a roof is expensive and they generally last 20 or more years depending on the materials used and the skill of the installer. Thus, there is a huge installed base of roofs with old technology vents that should be upgraded to include the latest in weather, fire and ember resistance.

SUMMARY

The devices and methods described below provide for flame, ember and rain resistant vent inserts for existing installed roof vents that do not require breaking the weather resistant membrane of the roof or create damage to the surrounding building materials to install.

BRIEF DESCRIPTION OF THE DRAWINGS

FIG. 1 is a simplified perspective view of a building with ventilation through the roof.

FIG. 2 is a perspective view of a low profile roof vent suitable for use on the building of FIG. 1.

FIG. 3 is a cross section view of the vent of FIG. 2 taken along A-A.

FIG. 4 is a perspective view of a flat tile roof with a shape matching vent.

FIG. 5 is a perspective view of an S-type tile roof with a shape matching vent.

FIG. 6 is a cross section view of the vent of FIG. 4 taken along B-B.

FIG. 7 is a cross section view of the vent of FIG. 5 taken along C-C.

FIG. 8 is a side view of a low-profile roof vent and low profile vent insert.

FIG. 9 is a top view of the low-profile roof vent and low profile vent insert of FIG. 8.

FIG. 10 is a perspective view of a primary vent.

FIG. 11 is a top view of a flame, ember and rain resistant vent insert for an existing roof vent.

FIG. 12 is a bottom view of the flame, ember and rain resistant vent insert of FIG. 11.

FIG. 13 is a front view of the flame, ember and rain resistant vent insert of FIG. 11.

2

FIG. 14 is a back view of the flame, ember and rain resistant vent insert of FIG. 11.

FIG. 15 is a left side view of the flame, ember and rain resistant vent insert of FIG. 11.

FIG. 16 is a right side view of the flame, ember and rain resistant vent insert of FIG. 11.

FIG. 17 is a top perspective view of an M-type secondary vent.

FIG. 18 is a bottom perspective view of the vent of FIG. 14.

FIG. 19 is a side view of the vent of FIG. 14.

FIG. 20 is a top view of a flame, ember and rain resistant vent insert for an existing M-type roof vent.

FIG. 21 is a bottom view of the flame, ember and rain resistant vent insert of FIG. 20.

FIG. 22 is a front view of the flame, ember and rain resistant vent insert of FIG. 20.

FIG. 23 is a back view of the flame, ember and rain resistant vent insert of FIG. 20.

FIG. 24 is a left side view of the flame, ember and rain resistant vent insert of FIG. 20.

FIG. 25 is a right side view of the flame, ember and rain resistant vent insert of FIG. 20.

FIG. 26 is a top view of a flame, ember and rain resistant vent insert for an existing roof vent for flat clay and concrete tile.

FIG. 27 is a bottom view of the flame, ember and rain resistant vent insert of FIG. 26.

FIG. 28 is a front view of the flame, ember and rain resistant vent insert of FIG. 26.

FIG. 29 is a back view of the flame, ember and rain resistant vent insert of FIG. 26.

FIG. 30 is a left side view of the flame, ember and rain resistant vent insert of FIG. 26.

FIG. 31 is a right side view of the flame, ember and rain resistant vent insert of FIG. 26.

FIG. 32 is a top view of a flame, ember and rain resistant vent insert for an existing roof vent for S-type clay and concrete tile.

FIG. 33 is a bottom view of the flame, ember and rain resistant vent insert of FIG. 32.

FIG. 34 is a front view of the flame, ember and rain resistant vent insert of FIG. 32.

FIG. 35 is a back view of the flame, ember and rain resistant vent insert of FIG. 32.

FIG. 36 is a left side view of the flame, ember and rain resistant vent insert of FIG. 32.

FIG. 37 is a right side view of the flame, ember and rain resistant vent insert of FIG. 32.

DETAILED DESCRIPTION OF THE INVENTIONS

Buildings such as building 1 of FIG. 1 have one or more ventilation apertures, such as apertures 2A-2H, through the roof deck 1D to permit ventilation of the attic of the building. The ventilation apertures on the roof may be arranged with some apertures higher and or lower on the roof to optimize passive ventilation of the building. For example, the upper or upslope apertures 3 such as apertures 2A-2D are oriented high on the roof, upslope from the lower or downslope apertures 4, such as apertures 2E-2H. This orientation permits passive air circulation, convection, with outside air 5 entering the lower apertures and exiting the upper apertures as exhaust air 5X carrying heat and moisture from within the attic. Lower apertures may be located through the roof deck or alternatively or in addition to

having lower apertures on the roof deck one or more additional eave apertures **6** may be included under the eaves **1E** of the building.

The ventilation apertures **2A-2H** are protected by any suitable vent cover such as the low profile vent **10** of FIGS. **2** and **3** which is suitable for use with shingle, slate or shake roofs, flat tile vent **11** of FIGS. **4** and **6** which is suitable for use with flat clay or concrete roof tiles, S-type vent **12** of FIGS. **5** and **7** which is suitable for use with S-type clay or concrete roof tiles and M-type vent **13** of FIGS. **17**, **18** and **19** which is suitable for use with S-type clay or concrete roof tiles.

The low profile vent **10** of FIGS. **2** and **3** has vent flashing **10F** secured to the roof deck **1D** and is oriented with vent opening **16** in fluid communication with the ventilation aperture through the roof decking such as one of ventilation apertures **2A-2H**. Vent **10** includes a downslope vent opening **17** in fluid communication with vent cavity **18**, between flashing **10F** and vent cover **10C**, as well as vent opening **16**. Vent cavity **18** has an internal height of **18H** at the downslope edge **16D** of vent opening **16** and minimum internal height **18M** at the upslope edge **16U** of vent opening **16**.

Vents **10**, **11**, **12** and **13** and any other suitable vent installed on a roof may be updated to provide extreme weather protection as well as fire and ember protection by the insertion of an appropriate vent insert, such as low profile vent insert **20** illustrated in FIGS. **11** through **16**, which may be inserted in vent cavity **18** of low-profile vent **10** through the downslope opening **17** and then secured to the vent, surrounding roofing and or roof deck using any suitable fasteners and or caulking or mastic as illustrated in FIGS. **8** and **9**.

Flame, ember and rain resistant vent inserts for each style vent include one or more of each optional elements discussed below which are formed from, or secured to insert base or frame **24** which is shaped to conform to the shape of the vent sub-flashing or vent skeleton. For example, each vent insert, such as flame, ember and rain resistant low profile vent insert **20**, may include an external diverter **21** with weep holes, an internal filter **22**, a downslope filter **23** to provide a general filter for downslope vent openings such as downslope vent opening **17** of low profile vent **10**. Internal filter **22** includes one or both of a screen **22A** to perform gross filtering and or filter mesh **22B** which provides fine filtration and filters and prevents passage of embers and other solids. Internal filter **22** is sized to surround at least 3 sides of vent opening **16** and to span the internal height **18H** at the downslope edge **16D** and compress to fit in minimum internal height **18M** at the upslope edge **16U**.

Insertion of a vent insert, such as vent insert **20**, is performed by orienting insert base **24** parallel to, and co-planer with, sub-flashing **10F** with the internal filter **22** between the downslope vent opening **17** and the external diverter **21**. The vent insert **20** is pushed into the downslope vent opening with internal filter **22** leading as illustrated in FIGS. **8** and **9**. Vent insert **20** is inserted until downslope filter **23** obstructs downslope vent opening **17** and the external diverter remains outside the downslope vent opening. Once fully inserted, the vent insert is secured to the roof deck or to the vent skeleton as appropriate.

The separate components of filter **22**, screen **22A** and filter mesh **22B** are secured to and supported by insert base **24**. Screen **22A** and filter mesh **22B** are secured to insert base filter legs **24L**, **36L**, **46L** and **56L** using any suitable material or technique, including without limitation adhesion, weld-

ing, fastening, wrapping, stitching and the like. The insert base filter legs, such as filter legs **24L**, **36L**, **46L** and **56L**, may optionally include one or more tabs, fingers or other elements extending from the filter leg such as filter fingers **27** which may be folded to engage either or both of screen **22A** and filter mesh **22B** as illustrated in FIGS. **12**, **15** and **16**. Downslope filter **23** and screen **22A** are any suitable ventilation screen such as $\frac{1}{4}$ " steel mesh although any suitable material and mesh size may be used such as $\frac{1}{8}$ " mesh made of stainless steel, brass, copper, plastic, intumescent material or other. Filter mesh **22B** is a flame-resistant interwoven mesh which may be any suitable material such as stainless steel. In a preferred configuration, filter mesh **22B** is stainless steel wool made from alloy type AISI 434 stainless steel which forms a pad approximately $\frac{1}{4}$ " thick. Filter mesh **22B** is secured to screen **22A** and/or insert base **24**.

External diverter **21** spans all or a significant portion of the horizontal expanse of downslope vent opening **17** to prevent direct flow of fire, flame, embers and wind driven rain or other material into downslope vent opening **17**. Each external diverter, such as external diverter **21**, has one or more weep holes, such as weep holes **25** to prevent water retention by the external diverter. The weep holes, such as weep holes **25** are arranged along, and span, the intersection of external diverter **21** and insert base **24**, known as drain line **26**. Weep holes, such as weep holes **25**, may adopt any suitable shape such as a closed curve, any suitable polygon, heart shape, star shape, triangle shape and the like.

Vent insert **20** may include only insert base **24** and external diverter **21**; or vent insert **20** may include only insert base **24** and downslope filter **23**; or vent insert **20** may include insert base **24** and screen **22A**; or vent insert **20** may include or insert base **24** and filter mesh **22B**. Alternatively, vent insert **20** may include any suitable combination of external diverter **21**, downslope filter **23**, screen **22A** and or filter mesh **22B**. A vent insert such as vent insert **20** with at least screen **22A** and or filter mesh **22B** may include one or more tabs, fingers or other elements extending from the filter leg of the vent insert such as filter fingers **27** to engage either or both of screen **22A** and or filter mesh **22B**.

Two-piece vents, such as flat tile vent **11**, S-type vent **12** or M-type vent **13**, include a primary vent **14** as illustrated in FIGS. **6**, **7** and **10**. Primary vent **14** includes any suitable insect/vermin and debris barrier, such as screen **14S**, and is installed on a roof deck, such as deck **1D** of FIG. **1**, over a ventilation opening or aperture, such as ventilation apertures **2A-2H**, cut through the deck.

Referring now to FIGS. **17**, **18** and **19**, M-type vent **13** has a skeleton **13S** parallel to cap **13C**. The orientation of skeleton **13S** and cap **13C** create a downslope vent opening **30** in fluid communication with vent cavity **31** formed between skeleton **13S** and cap **13C**. Skeleton **13S** includes secondary ventilation openings **32A**, **32B** and **32C**.

M-type vent insert **36** is illustrated in FIGS. **20** through **25**. Vent insert **36** includes an insert base **36B** and may be inserted in vent cavity **31** of low-profile vent **10** through the downslope opening **30** and insert base **36B** is secured to the vent skeleton **13S** using any suitable fasteners and or caulking or mastic. M-type vent insert **36** includes an external diverter **37** with weep holes **25**, internal filter **38** and a downslope filter **39** to provide a general filter for downslope vent openings such as downslope vent opening **30** of M-type vent **13**. Internal filter **38** is sized to surround at least three sides of a portion of vent cavity **31** composed of the space between secondary ventilation openings **32A**, **32B** and **32C** and vent cap **13C**. Internal filter **38** is composed of a screen

22A for structure and filter mesh 22B to filter and prevent passage of embers and other solids into secondary ventilation openings 32A, 32B and 32C. Internal filter 38 is sized to span the distance between skeleton 13S and vent cap 13C.

Flat tile vent 11 of FIGS. 4 and 6 has a skeleton 11S parallel to cap 11C. The orientation of skeleton 11S and cap 11C create a downslope vent opening 40 in fluid communication with vent cavity 41 formed between skeleton 11S and cap 11C. Skeleton 11S includes a secondary ventilation opening 42.

Flat tile vent insert 46 is illustrated in FIGS. 26 through 31. Vent insert 46 includes an insert base 46B and may be inserted in vent cavity 41 of flat tile vent 11 through the downslope opening 40 and insert base 46B is secured to the vent skeleton 11S using any suitable fasteners and or caulking or mastic. Flat tile vent insert 46 includes an external diverter 47 with weep holes 25, internal filter 48 and a downslope filter 49 to provide a general filter for downslope vent openings such as downslope vent opening 40 of flat tile vent 11. Internal filter 48 is sized to surround at least three sides of a portion of vent cavity 41 composed of the space between secondary ventilation opening 42 and vent cap 11C. Internal filter 48 is composed of a screen 22A for structure and filter mesh 22B to filter and prevent passage of embers and other solids into secondary ventilation opening 42. Internal filter is sized to span the distance between skeleton 11S and vent cap 11C.

S-type vent 12 of FIGS. 5 and 7 has a skeleton 12S parallel to cap 12C. The orientation of skeleton 12S and cap 12C create a downslope vent opening 50 in fluid communication with vent cavity 51 formed between skeleton 12S and cap 12C. Skeleton 12S includes first and second secondary ventilation openings 52A and 52B.

S-type vent insert 56 is illustrated in FIGS. 32 through 37. Vent insert 56 includes an insert base 56B and may be inserted in vent cavities 51 of S-type tile vent 12 through the downslope opening 50 and insert base 56B is secured to the vent skeleton 12S using any suitable fasteners and or caulking or mastic. S-type vent insert 56 includes an external diverter 57 with weep holes 25, first internal filter 58A, second internal filter 58B and a downslope filter 59 to provide a general filter for downslope vent openings such as downslope vent opening 50 of flat tile vent 12. Each of first and second internal filters 58A and 58B are sized to surround at least three sides of a portion of vent cavity 51 composed of the space between first or second secondary ventilation openings 52A and 52B respectively and vent cap 12C. Internal filters 58A and 58B are composed of a screen 22A for structure and filter mesh 22B to filter and prevent passage of embers and other solids into first and second secondary ventilation openings 52A and 52B. Internal filters 58A and 58B are sized to span the distance between skeleton 12S and vent caps 12C.

Flame, ember and rain resistant vent inserts, such as vent inserts 20, 36, 46 and 56, may also be removable from the permanent vent installed on a roof. Removing a previously installed flame, ember and rain resistant vent insert may enable the replacement of clogged or damaged elements such as screens or intumescent screens that have been exposed to extreme heat or to add additional features not include on the originally installed vent insert.

While the preferred embodiments of the devices and methods have been described in reference to the environment in which they were developed, they are merely illustrative of the principles of the inventions. The elements of the various embodiments may be incorporated into each of the other species to obtain the benefits of those elements in

combination with such other species, and the various beneficial features may be employed in embodiments alone or in combination with each other. Other embodiments and configurations may be devised without departing from the spirit of the inventions and the scope of the appended claims.

We claim:

1. An improved ventilation system for a building, the building having a roof deck with one or more ventilation apertures therethrough and a layer of roof shingles attached to the roof deck and one or more roof vents interspersed among the roof shingles, each of the one or more roof vents having an upslope edge, a downslope edge, a vent cover secured to a sub-flashing forming a vent cavity therebetween and a downslope vent opening along the downslope edge of the one or more roof vents, the sub-flashing including a ventilation opening in fluid communication with at least one of the one or more ventilation apertures, the vent cavity and the downslope vent opening, the improved ventilation system comprising:

a flame, ember and rain resistant vent insert operable to be inserted through the downslope vent opening of one of the one or more roof vents and secured to the roof deck and or the one or more roof vents, comprising:

a generally planar insert base;

an external diverter oriented perpendicular to and intersecting the generally planar insert base along a drain line;

a plurality of weep holes, through the generally planar insert base and the external diverter, intersecting the drain line;

an internal filter having a structural screen combined with a filter mesh, the internal filter is sized to surround at least 3 sides of the ventilation opening and to span the vent cavity from the vent cover to the sub-flashing; and a downslope filter operable to obstruct the downslope vent opening.

2. A flame, ember and rain resistant vent insert for a roof vent having a downslope vent opening, a vent cavity and one or more secondary vent openings in fluid communication with the vent cavity and the downslope vent opening, the flame, ember and rain resistant vent insert comprising: an insert base with a plurality of filter legs extending therefrom; and at least one of an external diverter, an internal filter or a downslope filter secured to the insert base with the plurality of filter legs.

3. The flame, ember and rain resistant vent insert of claim 2 wherein the insert base with the plurality of filter legs extending therefrom includes an attached said external diverter oriented perpendicular to and intersecting the insert base along a drain line and a plurality of weep holes, through the insert base and the external diverter, intersecting the drain line; and at least one of the internal filter or the downslope filter.

4. The flame, ember and rain resistant vent insert of claim 2 wherein the insert base with the plurality of filter legs extending therefrom includes an attached said internal filter secured to the filter legs and to the insert base and to one of the downslope filter or the external diverter; and

the internal filter is sized to surround at least 3 sides of each of the one or more secondary ventilation openings and to span the vent cavity from a vent cap to a skeleton.

5. The flame, ember and rain resistant vent insert of claim 4 wherein the internal filter is comprised pf at least one of a structural screen or a filter mesh.

6. The flame, ember and rain resistant vent insert of claim 4 wherein the internal filter is comprised of a structural screen and a filter mesh.

7. The flame, ember and rain resistant vent insert of claim 2 wherein the insert base with the plurality of filter legs extending therefrom includes an attached said downslope filter operable to obstruct the downslope vent opening and the internal filter formed of a structural screen sized to surround at least 3 sides of each of the one or more secondary vent openings and to span the vent cavity from a vent cap to a skeleton.

8. The flame, ember and rain resistant vent insert of claim 2 wherein the insert base with the plurality of filter legs extending therefrom includes an attached said downslope filter operable to obstruct the downslope vent opening and the internal filter formed of a filter mesh sized to surround at least 3 sides of each of the one or more secondary vent openings and to span the vent cavity from a vent cap to a skeleton.

9. The flame, ember and rain resistant vent insert of claim 2 wherein the insert base with the plurality of filter legs extending therefrom includes an attached said downslope filter operable to obstruct the downslope vent opening and the internal filter formed of a structural screen and a filter mesh sized to surround at least 3 sides of each of the one or more secondary vent openings and to span the vent cavity from a vent cap to a skeleton.

10. The flame, ember and rain resistant vent insert of claim 2 wherein the roof vent includes a sub-flashing and the insert base is generally planar.

11. The flame, ember and rain resistant vent insert of claim 2 wherein the roof vent includes a skeleton and the insert base corresponds to the shape of the skeleton.

12. The flame, ember and rain resistant vent insert of claim 11 wherein the roof vent is a flat tile vent.

13. The flame, ember and rain resistant vent insert of claim 11 wherein the roof vent is an M-type vent.

14. The flame, ember and rain resistant vent insert of claim 11 wherein the roof vent is an S-type vent.

15. The flame, ember and rain resistant vent insert of claim 2 wherein the roof vent is a low profile vent with a sub-flashing.

16. An improved ventilation system for a roof having a roof deck, at least one ventilation aperture therethrough and a layer of roof shingles attached to the roof deck and at least one roof vent having an upslope edge, a downslope edge, a vent cover secured to a sub-flashing forming a vent cavity therebetween and a downslope vent opening along the downslope edge of the at least one roof vent, the sub-flashing having a ventilation opening in fluid communication with the at least one ventilation aperture, the vent cavity and the downslope vent opening, the improved ventilation system comprising:

a flame, ember and rain resistant vent insert operable to be inserted through the downslope vent opening of one of the at least one roof vents and secured to the roof deck and or the at least one roof vent, comprising:

a generally planar insert base; an external diverter oriented perpendicular to and intersecting the generally planar insert base along a drain line;

a plurality of weep holes, through the generally planar insert base and the external diverter, intersecting the drain line;

an internal filter having a structural screen combined with a filter mesh, the internal filter is sized to surround at least 3 sides of the ventilation opening and to span the vent cavity from the vent cover to the sub-flashing; and a downslope filter operable to obstruct the downslope vent opening.
